CONCRETE PIPE MAKING MACHINE

Charles C. Quinn and Harley Edgerton, Boone,
Iowa, assignors to Quinn Wire & Iron Works,
Boone, Iowa, a corporation of Iowa

Application December 9, 1929, Serial No. 412,803

12 Claims. (Cl. 74—22)

This invention relates to improvements in that type of machines for making cement pipe, and particularly to that type employing a vertical and rotatively and slidably mounted packer shaft, having at its lower end a packer head and core member arranged to be moved longitudinally through a tile form, as the tile is formed therein.

The object of our invention is to provide in a machine of the class above described improved means for supporting, elevating and lowering the packer shaft, whereby said shaft will be slidably supported against lateral movement, and whereby lifting power may be applied to the shaft in such manner that any tendency toward swinging either end of the shaft laterally will be practically eliminated, and any frictional loss caused by said swinging action will be eliminated.

A further object of our invention is to provide improved means for imparting rotary movement to the shaft, whereby friction and wear caused by the longitudinal movement of the shaft relative to the means for rotating the shaft will be greatly reduced.

A further object is to provide means whereby the sliding speed of said shaft may be varied relative to its rotating speed.

Our invention consists in the construction, arrangement and combination of the various parts of the device, whereby the objects contemplated are attained, as hereinafter more fully set forth, pointed out in our claims, and illustrated in the accompanying drawings, in which:

Figure 1 is a side elevation of a tile making machine embodying our improvements; the mechanism for elevating, lowering and rotating the packer shaft being shown in section, and a portion of the tile form being broken away.

Figure 2 is a detail sectional view taken on the line 2—2 of Figure 1.

Figure 3 is a detail sectional view taken on the line 3—3 of Figure 1.

Figure 4 is a front elevation of the upper end of the mechanism for rotating and supporting the packer shaft.

Figure 5 is a vertical sectional view of the mechanism for rotating the packer shaft.

Referring to the drawings, we have used the reference numeral 10 to indicate the frame of the pipe machine, the upper end of which supports an auxiliary frame member 11 comprising a pair of parallel and spaced side members 12. One end of said side members projects forwardly beyond the front of the frame 10. Each forwardly projecting portion 13 is designed to support an upright frame member 14.

The upper ends of the frame members 14 are provided with what we shall term an upper bearing block 15, having spaced bearings 16 in which is rotatively mounted a shaft 17. Each end of the shaft 17 is provided with a sprocket wheel

18. The block 15 is provided with a bearing 19 for rotatively receiving the upper end of a vertically arranged tubular shaft 20. The lower end of said tubular shaft 20 is rotatively mounted in a block 21, fixed to the side members 13. The lower end of the tubular shaft 20 is mounted in the hub of a bevel gear 22 rotatively mounted in the block 21 by suitable bearings 23. The bevel gear 22 is driven by means of a pinion 24 mounted on the outer end of a horizontally arranged shaft 25 rotatively mounted in suitable bearings 26 and 27 secured to the frame members 12. The inner end of the shaft 25 is provided with a sprocket 18 driven by a chain 29 through the sprocket 30 mounted on a drive shaft 31, which is provided with a belt wheel 32, which may be rotated by any suitable power.

The lower end of the tubular shaft 20 is provided with a bearing member 33, and the upper end with a bearing member 34. Said bearings 33 and 34 are designed to rotatively and slidably support a packer shaft 35, which is provided at its lower end with a packer head 36 and a core member 37. Said packer head and core member are designed to move vertically in a cylindrical form 38 of larger diameter than the core 37, so that an annular space 39 is provided between the core 37 and the inner walls of the form 38, the width of which is equal to the thickness of the pipe to be made therein.

The pipe is formed by introducing plastic cement or concrete in the upper end of the form 38 at the time the core 37 is at its lower limit of movement, then rotating the core 37 and the packer 36, and at the same time elevating the same.

For elevating the packer shaft, we have provided a cam shaft 40 mounted in suitable bearings on the frame members 12. Said shaft 40 is rotated by means of a worm gear 41 secured to its central portion and mounted in a suitable casing 42. The bottom of the casing 42 is provided with a worm 43 in mesh with the gear 41 and mounted on a drive shaft 44. Said drive shaft 44 has a sprocket wheel 45 driven by means of a chain 46 from the sprocket 47 mounted on the shaft 31.

Each end of the shaft 40 is provided with a cam 48. Adjacent to the outer side of each of the cams 48 is a lever 49, having its rear end pivotally connected to a shaft 50 mounted in suitable brackets 51 secured to the rear end of the members 12. The central portion of each of the levers 49 is provided with a stub shaft 52 provided with a roller 53 designed to engage the under surface of the cams 48. The free end of each of the levers 49 is provided with a sprocket 54.

The upper bearing block 15 is provided with a rearwardly extending bracket 55 designed to sup-

- port a vertically arranged rod 56, the upper end of the rod being adjustably mounted therein by means of a nut 57. An equalizing bar 58 is pivotally connected to the lower end of the rod 56.
- 5 Each end of the equalizing bar has one end of a chain 59 connected thereto. Said chains are designed to pass under the sprockets 18, having their free ends depending adjacent to the opposite sides of the tubular member 20, and connected to what we shall term a tappet block support 60. Said support 60 is slidably mounted on the tubular shaft 20 and provided at its rear side with a cross head 61 slidably mounted in vertical guides 62 supported by the frame members 14. The cross head 61 is connected to the block 60 by means of a suitable pin 63. The upper face of the block 60 is provided with a circular recess 64 in which is rotatively mounted a bearing member 65.
- 10 20 Fixed to the packer shaft 35 is a tappet block 66, preferably formed of two pieces secured together by suitable bolt 67 in such manner that the blocks will rigidly clamp the shaft. One of the blocks is provided with a key 68 to prevent 25 rotation of the block about said shaft. Each member of the block 66 is provided with an outwardly projecting portion 69 provided with a roller pin 70. Said members 69 and the pins 70 are designed to project through longitudinal slots 30 71 in the tubular shaft 20, said slots being of a length equal to the amount of longitudinal movement of the shaft 35. Each of the roller pins 70 is provided with a roller 72 so arranged that its periphery will engage one edge of the corresponding slot in the manner illustrated in Figure 3. The face of the edge of the slot and the contacting portions of the rollers are in a plane 35 extending through the center of the shaft 35.
- 35 By this construction any tendency toward lateral movement between the contacting edges of the slots 71 and said rollers will be eliminated as rotary power is applied to the cylinder shaft. Thus means is provided whereby the shaft 35 will be rotated when in any of its elevated or lowered positions, and provides means whereby the friction between the shafts 20 and 35 will be eliminated as the shaft 35 is moved longitudinally of the shaft 20.
- 40 The outer ends of the pins 70 are mounted in bearings 73 carried by the bearing member 65. By this arrangement the shaft 35 is elevated and lowered by means of the bearing 65, which in turn is elevated and lowered by the block 60 and the chains 59.
- 45 50 The practical operation of our device is as follows:
- 55 Assuming that the packer head 36 and the core 37 are mounted in the form 38 and are at their lower limit of movement, then the sprockets 60 64 will be at their upper limits of movement, in the manner shown in Figure 1. The shaft 31 is then rotated, which in turn will cause the shafts 25 and 44 to be rotated by the chains 29 and 46. The shaft 20 will then be rotated by means of 65 the bevel gears 22 and 24 and the shaft 40 will be rotated by means of the worm gear 41 and the worm 43. The cams 48 will then cause the free ends of the levers 49 to move downwardly, causing the depending ends of the chains 59 to be elevated and with them the tappet supporting block 60, which in turn will cause the packer shaft 35 to be elevated by means of the tappet block 66.
- 70 75 By this arrangement it will be seen that the elevating speed of the packer shaft may be varied

by varying the shape of the cams 48, and thus provide means whereby the shaft 35 may be elevated slowly as it moves upwardly through the form 38 and having its speed increased as the core members are moved above said form, while the downward movement of the shaft may be quite rapid.

The weight of the packer head and core, as well as the tappet supporting block, provides the necessary power for the downward movement, and at the same time for elevating the free ends of the levers 49, so that the rollers 53 are always in contact with the periphery of the cams 48.

The equalizing bar 58 provides means whereby the equal strain will always be imparted to the chains 59, and whereby the same lifting strain will always be imparted to each side of the tappet block support 60 to cause the said block to slide readily on the shaft 20 without binding.

The sprockets 18 are so located that the depending ends of the chains 59 are parallel with the shaft 35, thereby eliminating any tendency for lateral movement of the tappet block support relative to the shaft 20.

The said tappet block support is held against 25 rotary movement about the shaft 20 by the cross head 61, which operates and guides parallel with the shaft 35. By this arrangement the central portion of the tubular shaft 20 is supported against any buckling strain which would be the 30 greatest when the tappet block is midway between the ends of the shaft 20.

It sometimes happens that it is desirable to increase or decrease the speed of rotation of the shaft 20 relative to the speed of the shaft 40. 35 This may be easily and quickly accomplished by simply changing the sprockets 30 and 47.

Thus it will be seen that we have provided improvements in pipe making machines whereby the friction caused by the power being transmitted from the rotating tubular shaft to the 40 slidably mounted power shaft is greatly reduced, and whereby the wear on said parts will be reduced.

It will be seen that we have provided improved 45 means for elevating and lowering the packer shaft, whereby the movement of the lifting force is always maintained in the longitudinal axis of said shaft, thereby permitting free up and down movement of said shaft.

We claim as our invention:

1. In a device of the class described, a support, a vertical tubular shaft rotatively mounted therein having oppositely arranged longitudinal slots, a packer shaft slidably mounted axially in said tubular shaft, a tappet block rigidly secured to said shaft, said block having rollers for engaging one edge of each of said slots, the contact surfaces of said rollers and slots being in a plane projecting through the axis of said shaft, means 55 for moving said tappet block longitudinally of said tubular shaft, and means for rotating said tubular shaft.

2. In a device of the class described, a support having guides, a vertical tubular shaft rotatively mounted therein having oppositely arranged longitudinal slots, a packer shaft slidably mounted axially in said tubular shaft, a tappet block rigidly secured to said packer shaft, said block having 60 rollers for engaging one edge of each of said slots, the contact surfaces of said rollers and slots being in a plane projecting through the axis of said shaft, a tappet block support slidably mounted on said guides, means for elevating and lowering 65

- said tappet block, and means for rotating said tubular shaft.
3. In a device of the class described, a support having guides, a vertical tubular shaft rotatively mounted therein having oppositely arranged longitudinal slots, a packer shaft slidably mounted axially in said tubular shaft, a tappet block rigidly secured to said packer shaft, said block having rollers for engaging one edge of each of said slots, a tappet block support slidably mounted on said guides, means for elevating and lowering said tappet block at variable speeds, and means for rotating said tubular shaft at a constant speed.
4. In a device of the class described, a support having guides, a vertical tubular shaft rotatively mounted therein having oppositely arranged longitudinal slots, a packer shaft slidably mounted axially in said tubular shaft, a tappet block rigidly secured to said packer shaft, said block having rollers for engaging one edge of each of said slots, a tappet block support slidably mounted on said guides, means for elevating and lowering said tappet block at variable speeds, means for rotating said tubular shaft at a constant speed, and means for varying the speed ratio of the last two said means.
5. In a device of the class described, a support having guides, a vertical tubular shaft rotatively mounted therein having oppositely arranged longitudinal slots, a packer shaft slidably mounted axially in said tubular shaft, a tappet block rigidly secured to said packer shaft, said block having rollers for engaging one edge of each of said slots, a tappet block support slidably mounted on said guides, means for elevating and lowering said tappet block, said means comprising a cam shaft, means for rotating said shaft, a pair of similar cams on said shaft, a lever operated by each of said cams, a sprocket wheel carried by the movable end of each of said levers, a pair of sprocket wheels on the upper end of said support, a pivoted equalizing bar, a chain connected to each end of said equalizing bar and passing under corresponding sprockets of said levers and over the corresponding sprockets of said support, and having its ends depending and connected to said tappet block support at diametrically opposite points.
6. In a device of the class described, a support having vertical guides and upper and lower bearing blocks, a tubular shaft having its ends rotatively mounted in said bearings, said tubular shaft having longitudinal and opposite slots, a packer shaft slidably mounted axially within said tubular shaft, a tappet block secured to said packer shaft having roller pins projecting through said slots, a roller on each pin designed to engage one edge of a corresponding slot, a tappet block support slidably mounted on said tubular shaft and in said guides, means for applying lifting force to said tappet block support to move the tappet block support longitudinally of said tubular shaft, and means for rotating said tubular shaft.
7. In a device of the class described, a support having vertical guides and upper and lower bearing blocks, a tubular shaft having its ends rotatively mounted in said bearings, said tubular shaft having longitudinal and opposite slots, a packer shaft slidably mounted axially within said tubular shaft, a tappet block secured to said packer shaft having roller pins projecting through said slots, a roller on each pin designed to engage one edge of a corresponding slot, a tappet block support slidably mounted on said guides, means for lifting said tappet block support, and means for rotating said tubular shaft.
8. In a device of the class described, a support having vertical guides and upper and lower bearing blocks, a tubular shaft having its ends rotatively mounted in said bearings, said tubular shaft having longitudinal and opposite slots, a packer shaft slidably mounted axially therein, a tappet block fixed to said packer shaft having roller pins projecting through said slots, a roller on each pin having its periphery in engagement with one edge of a corresponding slot, the contact surface of said rollers and said slots being in a plane projecting through the axis of said packer shaft, means for lifting said tappet block, and means for rotating said tubular shaft.
9. In a device of the class described, a tubular driving shaft, having a longitudinal slot, a driven shaft slidably mounted axially therein, a tappet block secured to said shaft having a roller pin projecting through said slot, a roller on said pin designed to engage one edge of said slot, the contact surface of said roller and said slot being in a plane projecting through the longitudinal center of said shaft, means for lifting said tappet block support, and means for rotating said tubular shaft.
10. In a device of the class described, a tubular driving shaft, having a longitudinal slot, a driven shaft slidably mounted axially therein, a tappet block secured to said shaft having a roller pin projecting through said slot, a roller on said pin designed to engage one edge of said slot, the contact surfaces of said roller and said slot being in a plane projecting through the longitudinal center of said shaft.
11. In a device of the class described, a support having vertical guides, a tappet block slidably mounted in said guides, a packer shaft carried by said tappet block, means for rotating said tappet block, means for elevating and lowering said tappet block, the last means comprising a cam shaft, means for rotating said shaft, a pair of similar cams on said shaft, a lever operated by each of said cams, a sprocket wheel carried by the movable end of each of said levers, a pair of sprocket wheels on the upper end of said support, a pivotally supported equalizing bar, a chain for each corresponding set of sprockets passing under the sprockets of said levers and over the corresponding sprockets of said support, said chains having their free ends depending from the last sprockets and connected to said tappet block at diametrically opposite points.
12. In a device of the class described, a vertical packer shaft, a tappet block for supporting said shaft, means for rotating said shaft, means for elevating and lowering said tappet block, said means comprising a cam shaft, means for rotating said shaft, a pair of similar cams on said shaft, a lever operated by each of said cams, a sprocket wheel carried by the movable end of each of said levers, a pair of sprocket wheels on the upper end of said support, a pivoted equalizing bar, a chain connected to each end of said equalizing bar and passing under corresponding sprockets of said levers and over the corresponding sprockets of said support, and having its ends depending and connected to said tappet block at diametrically opposite points.

CHARLES C. QUINN.
HARLEY EDGERTON.
